AUTOMATIC STOKER AND CONTROL
THEREFOR

Walter A. Maynard, Cleveland Heights, Ohio

Application March 20, 1933, Serial No. 661,719

3 Claims. (Cl. 60—52)

My invention is an improvement in stokers and relates more particularly to hydraulically operated stokers and an automatic control therefor.

One of the objects of my invention consists in utilizing variations in pressure in the motive fluid to control the cycle of operation automatically under operating conditions, including such conditions which may arise as a result of foreign objects fed into the stoker hopper along with the fuel.

Another object of my invention is to provide full automatic operating control of a stoker mechanism hydraulically, and with minimum power.

15 A further object is to provide a control of the character described which may be furnished as a unit and independently of the device operated thereby, and which is capable of standardization in manufacture.

20 A still further object of my invention is to provide an operating control which is simple of construction and inexpensive to manufacture.

25 Another object of my invention is to construct an automatic stoker of the class described which may be operated and controlled by hydraulic means associated therewith either directly or remotely.

30 Other objects and advantages of my invention will become more apparent as the following description of several embodiments thereof progresses, reference being made to the accompanying drawings in which like reference characters are employed to designate like parts throughout.

In the drawings:—

35 Figure 1 is a longitudinal section through a stoker embodying my invention and illustrates the relative positions of the ram and operating mechanism just prior to feeding a charge of fuel forwardly of the stoker tube;

40 Figure 2 is similar to Figure 1, but shows the ram or plunger extended on its forward stroke;

Figure 3 is similar to Figure 2 and illustrates the relative positions of the parts just prior to the completion of one cycle of operation;

45 Figure 4 is a diagrammatic view of the hydraulic control;

Figure 5 illustrates a stoker embodying a modification of a part of my invention;

50 Figure 6 is a longitudinal section through a stoker embodying another modification of the present invention;

Figure 7 illustrates a form of valve forming part of my invention and shows the same in section taken on line 7—7 of Figure 11;

Figure 8 is a section taken on line 8—8 of Figure 7;

Figure 9 is a section taken on line 9—9 of Figure 7, and,

Figure 10 is a section through a multiple pressure oil pump used in connection with my invention.

Figure 11 is a section taken on line 11—11 of Figure 7; and,

Figure 12 is an enlarged view of a portion of Figure 4, illustrating in detail the by-pass valve, metering valve and relief valve.

In describing my invention as illustrated in the accompanying drawings, in which I have shown several embodiments, I shall refer to Figures 15 1 to 4 inclusive which illustrate the preferred form of the invention as applied in use.

In carrying out this form of the invention, the hopper 1 is carried by the casing or feeding tube 2 and communicates with the tube through an opening 3. The tube extends forwardly and terminates in a tuyère 4. A jacket 5 may be provided to supply air from the blower 6 as is indicated by the arrows, the air currents passing between the jacket and casing and then through suitable arranged openings 7 into the tuyère end of the feed tube. The stoker illustrated is of the underfeed type although it is to be understood that my invention is not limited to such use.

Within the tube 2 is a reciprocable sleeve 8 which is provided with an opening 9 in its upper wall for register with the hopper opening 3 to admit a charge of fuel into the sleeve and tube when the parts are in the position of Figure 1.

A stop 10 formed integrally with the casing 2 projects downwardly within the tube and serves to limit the movement of the sleeve 8 in either direction and also limits the forward stroke of the piston or plunger 11 operating within the sleeve 8.

In further carrying out my invention I have provided hydraulically operated means for operating the piston and sleeve according to a predetermined cycle of operation, wherein the piston 11, and the sleeve 8 having a charge of fuel delivered therein, are caused to move simultaneously in one direction to advance the charge bodily within the tube 2, although the sleeve and piston are capable of independent movement during any part of the cycle of operation, such for instance when foreign bodies are present in the fuel charge which might have a tendency to clog the passage of fuel through the opening 3.

This means includes the piston 11 which is slideable in the sleeve 8 and which is connected by a rod 12 to a head 13 operating in the cylinder 14.

carried by an end of the sleeve 8. Suitable ports 15, 16, 17 and 18 communicate with the interior of the cylinder and are arranged to admit and exhaust oil or other fluid under pressure from the cylinder. The right hand end of the cylinder 14 in the figures is formed with a head 19 which operates within the chamber 20. The chamber 20 is, of course, equipped with suitable ports 21, 22, 23 and 24 for the admission and exhaust of the operating fluid under pressure.

Before proceeding further with the description of the fluid operating means and automatic control thereof, I will briefly describe the modified forms of stoker construction which are particularly adapted to and form part of my invention. These are illustrated in Figures 5 and 6 and are somewhat similar to the form shown in Figures 1 to 3.

The form shown in Figure 5, however, is provided with a reciprocating sleeve formed either integral with or attached to the piston 11 to move therewith in either direction. The sleeve is open at 25 to permit the full charge to be delivered thereto when the same registers with the opening 3. A connecting rod 12 connects the piston 11 with a head 26 operating in a cylinder 27. Suitable ports 28 and 29 are provided for admitting fluid under pressure to either side of the head 26, while the stroke of the piston 11 may be predetermined by a pin placed in any one of the series of openings 30. A stop 31 limits the stroke of the piston 11 in one direction.

In Figure 6 the construction is very similar to that shown in Figure 5, but it will be noted that I have eliminated the sleeve 8 in its entirety.

Proceeding now with the description of the operating and control means, reference is made first to Figure 4 in which the general organization is illustrated in diagrammatic form. An electric motor 32 is connected to drive the oil pump 33, there being connections from the pump to an expansion chamber 34 to cushion any sudden changes in pressure in the line. A supply pipe 35 leads from the expansion chamber to the control valve 36 at 58.

A return conduit 37 connects the control valve 36 at 37a as shown in Figure 9 with the oil pump 33 while a conduit 38 leads from the conduit 35 through a pressure relief valve 39, a by-pass valve 40 and a metering valve 41 to a valve position motor 42, the oil or other fluid passing through these conduits under pressure being admitted to the motor 42 to operate the same. In this connection the metering valve of any well known construction serves to regulate the volume of fluid under pressure passing to the motor 42. A return pipe 43 returns some of the oil from the valve motor to the line 44 which has connection with the by-pass valve 40 and an oil reservoir 45. In this way the oil, after having passed through the valve motor is returned to the oil reservoir through the conduit 44 and may be passed through the pump again.

In Figures 7 and 8 I have illustrated in detail the control valve 36 and the driving motor 42. The motor 42 consists primarily of a casing 46 which houses a gear type of pump comprising the gears 47 and 48, the oil inlet being indicated at 49 and the outlet at 50 (Figure 4). The motor is preferably mounted on the valve casing and has a direct driving connection through a shaft 51 with the rotary valve member 52. The end 51a of the shaft is flattened to fit the slot 51b for a direct driving connection with the rotary plug 52. The valve casing 36 is provided with a

series of ports 53, 54 and 55 extending radially through the casing and adapted to register with a groove 56 formed lengthwise in the outer surface of the rotary member and communicating with an annular groove 57.

A port 58 formed in the valve casing always communicates with the groove 57. The plug or rotary member 52 is provided with a relief pressure opening 59a communicating the pressure side of the motor with the under side of the plug 52, and is also provided with an axial bore 59 extending throughout the length of the plug which will relieve pressures which might be built up under the plug. A zenith plug 60 communicates with the bore 59 to relieve pressures into the upper chamber 63. The zenith plug 60 is provided as a convenient means of controlling the relief of pressure through the bore 59, since this plug is provided with a restricted orifice as shown in Figure 7. The plug 60 is threaded for installation in a tapped hole in the plug 52 and may be interchanged with other plugs having larger or smaller orifices, if desirable, to adjust the operation of the valve. If the orifice in the plug 60 were too large, it would release too much fluid from the pressure side of the motor through 59a and consequently the motor would not receive sufficient pressure to turn the plug 52 to the next position in its cycle of operation. It will be noted that the plug 52 is tapered slightly downwardly and that pressure is exerted on the plug by means of a spring 61 to maintain it in seating relation with the inner walls of the casing. A groove 62 is also formed in the plug to register with any one or more of the ports 53, 54 or 55, depending on the position of the plug to deliver the oil to the upper chamber 63 formed in the valve casing. I have shown in Figure 7 the ports 53, 54 and 55 arranged or spaced at 120° intervals, this figure being a section taken on line 1-7 of Figure 11.

In order to exert a downward pressure on the plug 52, the spring 61 is preferably enclosed within the upwardly extending stem 64 formed on the plug, the upper extremity of the coil spring abutting the cap 65 which is removably secured to the valve casing 36. It is desired that the stem 64 extend upwardly to a point just out of contact with the cap to permit passage of oil from the lower part of the valve through the plug 60 and up into the chamber 63 over the top of the stem 64. Openings 66 are cut in the casing (Fig. 9) to permit overflow of oil from the chamber 63.

The valve stem 64 is formed as a cam of two or more sides in cross section (Figure 9), and operates between flat resilient members 67 and 68, the latter being bowed slightly intermediate its ends as illustrated. In this manner the plug when rotated throughout its cycle of operation will properly align its ports or grooves with the respective ports in the casing 36 during each successive step in the cycle. The springs 67 and 68 are supported in and extend across the casing as illustrated, the ends of the springs resting in the slots 66. Longitudinal displacement of the spring members 67 and 68 is prevented by the flange of the cap 65.

In Figure 10, the oil pump is shown in cross section and is of the usual gear type in which the driven shaft 70 connected with the electric motor 32, drives the pump gears 71 and 72 keyed to said shaft. Pump gears 73 and 74 are keyed to the idler shaft 75, the respective gears 71 and 73 and gears 72 and 74 being of corresponding sizes and 75

operating in separate pump compartments 76 and 77 to pump the oil through the respective outlets 78 and 79 at different volumes when the shaft 70 is rotated.

5 I will now describe the operation of the invention as particularly applied to Figures 1 to 4 inclusive.

Assuming that the control valve is connected to be operated as illustrated in the diagrammatic showing in Figure 4 and that the valve is connected to operate the embodiment shown in Figures 1 to 3 inclusive, the operation may be described as follows:

To begin the cycle of operation with the valve parts in the position shown in Figure 7 and the control units connected to the stoker as shown, the electric motor 32 is started and drives the pump 33 to force oil under pressure to the valve motor and the control valve 36. The volume of oil delivered by the pump is selective by means of the cocks 80 and 81, since either one of these may be closed if desired. Any suitable drive connection may be provided between the motor and pump and likewise a different type of pump may be used, if desired. Where operating conditions call for relatively uniform fuel feed at all times the simple type of gear pump is employed. Where variations from uniform feed are desirable, a compound gear pump or a type of adjustable or variable displacement pump may be used.

Since the volume output of the oil pump is relatively large as compared with the capacity of the valve position motor 46, it is desirable that some means be provided to slow down the speed of the valve motor. The oil line between the check valve and the valve motor is relatively small in diameter as compared with the line between the pressure relief valve and the by-pass valve. The by-pass valve is set so that it will open under relatively low pressure and allow the oil passed through the pressure relief valve to be returned to the intake of the oil pump or the oil reservoir, but at the same time maintains a moderate pressure and a constant supply of oil in the line to the valve position motor. This is sufficient to operate the valve position motor at moderate speed until the control valve is in the next position and the pressure in the oil pressure line is reduced.

Oil under pressure is delivered to the valve motor as already described. Oil under pressure is also delivered through the conduit 35 to the control valve 36 where it enters the valve through the port 58 and is communicated by means of the annular groove 57 and the groove 56 (Figure 7) to the outlet or port 55. This oil under pressure is thus communicated to one side of the piston head 19 in the chamber 20 as indicated more clearly in Figure 1. As the oil enters the chamber 20 under pressure it forces the head 19 and the cylinder 14 and the sleeve 8 to the left as indicated in Figure 2. This closes the opening 3 between the hopper and the interior of the tube and during the movement of the sleeve to the left the piston 11 is also thrust to the left with the sleeve until a wall of the sleeve and the piston abut the stop 10 extending into the sleeve 8. In this manner the charge of fuel is advanced in the sleeve and is ultimately delivered into the tuyère and into the fire pot of the furnace.

70 It will be noted that during this step in the operation of the invention the pressure is relieved on the opposite face of the head 19 through the port 23 which is connected with the control valve through the port 53 having communication with a groove 62 similar to the groove 62 formed in

the plug 52, to permit any oil which may remain in this part of the circuit to be discharged through the plug and out through the chamber 63 and the openings 66. The first part of the cycle of operation is thus complete.

The next step is illustrated in Figures 2 and 3 and represents the action occasioned by the rotation of the plug 52 by virtue of the actuation of the valve motor 42 to rotate the plug to a position where the grooves 56 and 57 are in communication with the port 53. The valve plug is rotated to the position as a result of pressure building up in the valve motor line after the piston 11 and sleeve 8 have reached their extreme limit of movement to the left in Figures 1 and 2. When the operation of this or any other part of the cycle is completed or the stoker is clogged, the movement of the operating piston is slowed down or stopped. The continued operation of the pump 33 will thus increase or build up the pressure in supply line 35. Pressure relief valve 39 is set to remain closed until the pressure rises to a predetermined degree, then it will open to communicate the fluid under pressure through the by pass 40 and metering valve 41 to the motor 42 which when actuated drives the valve plug 52 to the next consecutive position.

The valve is now in position to deliver oil under pressure as indicated in Figure 2 through the conduit 23 to the opposite face of the head 19, the pressure on the oil in the chamber 20 being relieved through the port 24 as the head 19 moves to the right by the admission of oil under pressure into the left hand end of the chamber 20 in Figure 2, the sleeve 8 is withdrawn to a position indicated in Figure 3 because of the fact that this oil under pressure is also admitted through the ports 17 and 18 to the interior of the cylinder 14, the piston 11 is maintained in its extreme left hand position until the head 19 reaches the right hand end of the chamber 20. Of course, the oil in the cylinder 14 and on the left hand face of the head 19, Figure 2, is released through the port 16, during the movement of the head 19 to the right.

During this part of the operation it will be seen that the piston 11 causes the charge of fuel to be advanced in the sleeve 8 while the said sleeve is withdrawn to the right. Upon completion of this step in the operation, the valve plug is again rotated through the medium of the valve motor to bring the grooves 56 and 57 into communication with port 54 whereupon oil under pressure will be transmitted through the conduit 16 to the left hand face of the piston 13 as indicated by the arrows in Figure 3. At the same time pressure is relieved through the conduit 23 and from the opposite face of the piston 13 through the ports 17 and 18 and the pistons 11 and 13 and the connecting rod 12 are then caused to travel to the right in Figure 3 to again assume the position of the parts in Figure 1 and to complete the cycle of operation of the invention. As the piston is returned to its extreme right hand limit of motion, it again uncovers the opening 3 between the hopper and the interior sliding sleeve 8 and permits the next charge of fuel to enter the sleeve. This cycle of operation is repeated automatically and in the manner described and fuel is thereby fed from the hopper and along the stoker tube and is discharged into the fire pot of the furnace.

The cycle control valve is so arranged that it not only distributes the oil under pressure to the proper cylinders in order throughout the cycle.

but also releases the oil from the other parts of the system where it is not to be under pressure and allows it to be returned to the inlet of the oil pump or to the oil reservoir. It is to be understood that the cycle control valve operates in a sort of step by step manner and is not in continuous motion. The valve position motor is operated automatically by the changes in pressure in the oil pressure lines as the cycle progresses so that it will turn the cycle control valve to the next desired outlet and leave it there until that part of the cycle of operation is complete and will then turn it automatically to the next port so that the cycle will be continued as long as the electric motor is running.

The valve position motor is an oil gear motor so arranged for driving the control valve that when oil is supplied to the motor under pressure it will revolve to turn the control valve to the desired position. For example, when oil under pressure is being delivered through the conduit 24, the pressure in the oil pressure lines will be proportional to the pressure required to move the sleeve 8 and piston 11 through the first stroke of the cycle of operation. When the end of that stroke is reached, the sleeve 8 or the piston 11 is stopped by the stop 10, and, as the oil pump continues to operate there is an immediate or relatively large increase of pressure in the oil pressure line. The pressure relief valve 39 may be set so that it will close off the line and will not open to relieve that pressure for any ordinary operating pressures that will occur during any part of the cycle when the sleeve or piston are moving. When the oil pressure is thus increased materially above such normal operating pressure, the pressure relief valve will open and release the oil under pressure to the valve position motor and through the by-pass valve to the inlet of the oil pump and the oil reservoir. The valve position motor then revolves and turns the cycle control valve to its next operating position. This releases the oil in the oil pressure lines so that the pressure in that line is materially reduced, the valve position motor stops rotating and leaves the cycle control valve in the proper position for the next step in the cycle of operation. This is continued automatically as long as the electric motor operates the oil pump. When it is desired to fill the sleeve 8 and the stoker tube with fuel prior to the actual operation of the stoker, this may be accomplished by first filling the hopper 1 with fuel and then closing the conduit 24 when the piston and sleeve are in the position shown in Figure 1. In this manner the sleeve 8 will remain stationary and the piston 11 will act alone as a ram to force the fuel through the tube 8 and the tuyère.

It will be seen that by my invention I have constructed a simple control mechanism which is particularly well adapted for the automatic control of stokers and which can be manufactured inexpensively because of such simplicity and the possibility of standardization of parts. The apparatus is so designed that it may be built in units and the stoker may be operated through the control means which may be, if desired, located in some remote place. It will also be seen that by my invention a wide range of operating conditions may be provided for with little or no change in the actual construction or arrangement of the parts. It is to be understood that while I have shown the control in connection with the automatic operation of a stoker, this

part of my invention can be suitably employed to control other apparatus if desired.

It will be observed that by the present invention ample power may be delivered to the stoker for the efficient feeding of fuel through the stoker and that in the event foreign objects are inadvertently fed through the hopper with the fuel and are of such size as might tend to clog the opening or unduly oppose the operation of the sleeve 8 and the piston 11, the piston may be operated independently of the sleeve to loosen up such clogged condition, and when the oil pressure operating the piston is materially increased above normal operating pressures, due to abnormal operating conditions such as clogging, the pressure relief valve will open and release the oil under pressure to the valve position motor and through the by-pass valve 40 to the inlet of the oil pump or the oil reservoir.

Various changes in the details of construction and arrangement of parts may be made without departing from the spirit of my invention or the scope of the appended claims.

I claim:

1. In a hydraulic control system including a source of fluid under pressure and a plurality of reciprocable members operated by said fluid under pressure, a distributing valve comprising a casing having a plurality of outlets communicating with said members, a rotatable plug within the casing having an opening in constant communication with said fluid source and progressively with said outlets as the plug is rotated, said plug having a discharge opening for simultaneous communication with another of said outlets to relieve pressure on one side of one of said reciprocable members while fluid under pressure is delivered to said one member in an opposite direction, and hydraulically operated means for rotating said valve, said last named means being responsive to variations in pressure on the fluid in said system.

2. In a hydraulic control system including a source of fluid under pressure and a plurality of reciprocable members operated by said fluid under pressure, a distributing valve comprising a casing having a plurality of outlets communicating with said members, a rotatable tapered plug fitting within the casing and having an opening in constant communication with said fluid source and progressively with said outlets as the plug is rotated, said plug having a discharge opening for simultaneous communication with another of said outlets to relieve pressure on one side of one of said reciprocable members while fluid under pressure is delivered to said one member in an opposite direction, said plug having a stem projecting axially therefrom, a spring within said stem to normally tend to thrust the plug inwardly of the casing, and means carried by the casing and engageable with the stem to align the respective communicating openings in the plug and casing as the plug is advanced throughout its succession of rotated positions.

3. In a hydraulic control system including a source of fluid under pressure and a plurality of reciprocable members operated by said fluid under pressure, a distributing valve comprising a casing having a plurality of outlets communicating with said members, a rotatable tapered plug fitting within the casing and having an opening in constant communication with said fluid source and progressively with said outlets as the plug is rotated, said plug having a discharge opening for simultaneous communication with another of said

outlets to relieve pressure on one side of one of said reciprocable members while fluid under pressure is delivered to said one member in an opposite direction, said plug having a stem projecting axially therefrom, a spring within said stem to normally tend to thrust the plug inwardly of the casing, and means carried by the casing and engageable with the stem to align the respective

communicating openings in the plug and casing as the plug is advanced throughout its succession of rotated positions, said last named means comprising a pair of resilient strips extending across the casing on opposite sides of said stem, said stem having at least two flat sides for engagement with said strips.

WALTER A. MAYNARD.
